United States Patent Office.

SAMUEL T. HEMINWAY, OF SARATOGA SPRINGS, NEW YORK.

Letters Patent No. 73,182, dated January 7, 1868.

IMPROVEMENT IN BURGLAR-ALARM LOCKS.

The Schedule referred to in these Letters Patent and making part of the same.

TO ALL WHOM IT MAY CONCERN:

Be it known that I, SAMUEL T. HEMINWAY, of Saratoga Springs, in the county of Saratoga, and State of New York, have invented a new and useful Door-Alarm Lock; and I do hereby declare that the following is a full, clear, and exact description thereof, reference being had to the accompanying drawings, making a part of this specification, in which—

Figure 1 is a perspective view of my invention, as combined with an ordinary door-lock.

Figure 2 is a sectional and more precise view of the main-spring wheel, pawl, and ratchet, showing the motive-power, and their bearings, as more particularly described hereinafter.

Similar letters of reference indicate corresponding parts in the several figures.

The object of my invention is to combine, with an ordinary door-lock, an alarm of sufficient capacity that, when adjusted to a door, and properly set, will give warning of the entrance of any person.

To enable others skilled in the art to make and use my invention, I will proceed to describe its construction and operation.

This improvement consists in arranging, in the inside of an ordinary door-lock, alarm-works, being respectively the main-spring wheel N and its attachments, escape-wheel G, verge F, and hammer E, combined with a certain arm, A, lever B, spring C, and its attached arm R, all acting in connection upon the latch-bolt D, that when the alarm-works are wound up, and lever B properly adjusted, by turning the knob of the lock connected with the latch-bolt D, either way upon the outside or inside of the door, the hammer E attached to the shaft of the verge F, and passing through an aperture, H, in the side of the lock, is affected, striking the bell I immediately attached to the outside of the lock, thereby causing an instantaneous and continued alarm for a definite length of time. By means of the pawl J, attached on the inside of the lock to the shaft K, as more particularly shown in fig. 2, which shaft passes through and is operated upon the outside of the lock, the ratchet-wheel L, attached to the arbor M of the main-spring wheel N, may be so affected as to hold the alarm-works in check when wound up. The main-spring-wheel arbor M, having its inside bearing upon the plate Q, passes to the outside of the lock, where the key P is attached, by which means the main-spring O is wound. The arm R is permanently connected with the spring C on the principle of a swivel, that when out through the aperture S in the side of the lock, the spring C may be confined by turning the arm R, so that its shoulders obstruct its passage through the aperture S, but by releasing the spring C, and allowing the arm R to pass in through the aperture S, the spring C rests against the lever B for the special purpose and to be used when a person passes out of the door and desires to leave the alarm set after closing the same. At other times the spring C can be confined as above described, and the alarm set by adjusting the arm-end of lever B, as set forth hereafter.

Having thus described my invention, and the manner of its operation, I now claim, and desire to secure by Letters Patent, the application following:

The combination and arrangement of the pivoted lever B, having its outer arm projecting through the aperture T on the top of the lock, the notched arm A secured to the verge, the spring C, and arm R, substantially as described, for the purpose specified.
